by

John Edward Lawrence.

United States Patent Office.

HENRY C. WIRE, OF WILMINGTON, OHIO.

Letters Patent No. 102,902, dated May 10, 1870.

IMPROVEMENT IN WIRE AND STONE FENCE COMBINED.

The Schedule referred to in these Letters Patent and making part of the same.

To all whom it may concern:

Be it known that I, HENRY C. WIRE, of Wilmington, in the county of Clinton and State of Ohio, have invented a new and improved Fence; and I do hereby declare that the following is a full, clear, and exact description thereof, reference being had to the accompanying drawings making part of this specification, in which—

Figure 1 is a side view of a section of my improved fence.

Figure 2 shows, by enlarged views, the mode of constructing the fence.

Similar letters of reference indicate corresponding parts in the two figures.

This invention relates to a novel mode of constructing fences, which is especially intended for parts of the United States where stone is abundant and wood is scarce.

The nature of my invention consists in constructing the parts of the fence of blocks or slabs of stone laid one upon another, and cemented together, at the same time laying down and adjusting the horizontal wires, which extend from post to post, between the blocks or slabs of stone forming the posts, so that, when the fence is completed, the said wires will be firmly held in their places imbedded between the blocks in the cement, as will be hereinafter explained.

The following is a description of my improved fence:

In the accompanying drawings—

A A represent stone posts, which may be constructed, say, fifty feet apart, and

c c are horizontal wires, which are arranged one above another, at suitable distances apart, and which pass through the posts or pillars, and are connected at the first post to a key-rod, D, as shown in figs. 1 and 2.

At intervals of, say, six feet, vertical wire binders B are applied to the horizontal wires, and connected in a suitable manner to stone anchors b.

The lowermost wire c c may be serrated and placed nearer together, in order to prevent hogs from getting through the fence.

To construct this fence, I select blocks, slabs, or pieces of stone of various sizes, and commence by laying down large stones for the foundation of the posts or pillars. I then adjust the wire c, which is nearest the ground, upon the foundation-stones, and then continue building up the posts by superimposing layer after layer of stones, arranging between every layer G, or between every alternate layer a, one of the wires, c.

The first post or pillar may be about eighteen inches

square; and the ends of the wires c may be secured by means of the vertical key-rod D, which receives eyes formed on the wires.

It will not be necessary to use cement in the construction of every one of the posts or pillars, as I have found a very substantial fence may be made by cementing the layers of stone a of every third or fourth post, the intermediate posts being constructed without cement, so that the weight of the stones alone will keep them in place.

To prevent longitudinal play of the wires c through the posts A, I shall serrate or barb those portions of the wires c which are imbedded in the posts, and lay the stones or cement about these portions, so that they will be firmly held.

The bars or serrations i may be made as shown in fig. 2, by means of a chisel.

It will be seen from the above description that I construct a fence of stone and wire combined, in such manner that the wires are applied to the posts and confined in place while building up these posts, thereby admitting of the use of small rough stones, such as are found in great abundance in various sections of this country, and dispensing with labor and expense which would be required to construct posts or pillars of dressed stone.

By thus utilizing the hitherto good-for-nothing stones, the posts or pillars do not require to be drilled for receiving through them the wires c, and a much stronger fastening of the wire to these posts or pillars can be effected.

I do not claim a combined wire and stone fence, when the posts are made of continuous solid blocks of stone, or of solid wood or solid iron, as my invention relates specially to a stone post made up of sections, between which sections the wires are placed and held.

Having described my invention,

What I claim as new, and desire to secure by Letters Patent, is—

1. A combined stone and wire fence, constructed by interposing the wires between layers of stone forming the posts or pillars, substantially as described.

2. A fence, composed of wires confined between layers of stone forming the posts or pillars, and anchored to stone blocks b, by the binding wires at intermediate points between the posts or pillars, substantially as described.

HENRY C. WIRE.
